UNITED STATES PATENT OFFICE.

JOHN F. ESSLER AND HENRY K. BERKHEIMER, OF MINNEAPOLIS, MINNESOTA.

METHOD OF AND APPARATUS FOR PRODUCING STOVE-DUFFS.

SPECIFICATION forming part of Letters Patent No. 508,002, dated November 7, 1893.

Application filed March 28, 1892. Serial No. 426,743. (No model.)

To all whom it may concern:

Be it known that we, JOHN F. ESSLER and HENRY K. BERKHEIMER, citizens of the United States, residing at Minneapolis, in the county of Hennepin and State of Minnesota, have invented certain new and useful Improvements in Methods of and Apparatus for Producing Stove-Duffs; and we do hereby declare the following to be a full, clear, and exact description of the invention, such as will enable others skilled in the art to which it appertains to make and use the same.

Our invention relates to what is known in the trade as cast metal duffs; and has for its object to cheaply produce such duffs with uniform flanges or dove-tail surfaces.

To this end our invention consists in the novel method of producing the said duffs and a special form of molding device for applying or carrying out the said method; which process or method and which device or apparatus will be hereinafter fully described and be particularly defined in the claims.

Our invention was especially designed for use in the production of stove duffs, or stove leg sockets; and will be herein illustrated and described, as applied for that purpose. It will be understood, however, that the invention might equally well be used for the production of duffs or dove-tail flanges of uniform flare on any other desired article.

In stoves, it is desirable to have the duffs or leg sockets of exactly uniform flare, so that they will accurately fit the shank of the stove leg. Otherwise it is difficult to properly secure the leg to the stove and the setting of the stove will be unstable. It is also desirable and even necessary to meet the competition in the trade, that the stove castings, including the duffs or leg sockets should be made very cheaply. These ends we accomplish by our invention.

Figures 1 and 2 are, respectively, an end elevation and plan view of the original male chill. Figs. 3, 4 and 5, are respectively, an end elevation, a transverse section, and a bottom view of the original female form. Figs. 6 to 18, inclusive, and Figs. 20, 21 and 22, are views partly in end elevation and partly in transverse section, illustrating various steps in the process. Fig. 19 is a plan view of a face-plate used in forming the guide-lugs.

Figs. 23 and 24 are respectively, a transverse section and a bottom view of a portion of the pattern provided with the guide-lugs. 55 Fig. 25 is a view in transverse section, showing the pattern, together with a pair of final female chills positioned thereon, embedded in the sand. Fig. 26 is a similar view to Fig. 25, showing the chills in position, and the impression left in the sand by the withdrawal of the pattern. Figs. 27 and 28 are respectively, views in sectional elevation and plan, showing the product of the process, or a portion of the stove base with the duffs cast 65 thereon.

Inasmuch as the different figures of the drawings are designed chiefly to illustrate the different steps of the process; the detailed description will be carried concurrently with the designation of the figures. The preferred or complete process for producing the best or most accurate form of duff will be first described; and thereafter, the dispensable steps will be noted, thereby disclosing the basis for the broad or generic claims. First. We start by making, from metal, either by hand or by machinery, what we call our original male form A'. This form is illustrated in end elevation and plan respectively in Figs. 1 and 2. It comprises the part a with a flange of the exact desired shape and a base a' which is of such shape as to permit the form to be withdrawn from the sand without disturbing the impression left 85 by the part a or flange proper. Second. We next make, by hand or machinery, what we call our rough or wooden female form B', which is made to fit freely over the male form A', and with its exterior shaped for reverse draft. This wooden form is shown in end elevation, cross section and plan respectively, in Figs. 3, 4 and 5. Third. These two originals A' and B' are then fitted together and embedded in the sand as shown in Fig. 95 6, and the wooden member is withdrawn, leaving the male member embedded as a chill. Fourth. From this male member A' as a chill and the impression left in the sand by the wooden member, as shown in Fig. 7, we cast a female chill B² which is illustrated in Fig. 8. This female chill B² will have its interior of a shape corresponding exactly to the exterior of the flange part a of the origi-

nal male form A', and will have its exterior of exactly the same form as the wooden original B'. Fifth. We next use the shrunk female chill B² and the original male form A', embedding the same in the sand, as shown in Fig. 9; and then, after withdrawing said male chill and leaving said female chill embedded in the sand as shown in Fig. 10, we cast therefrom and the impression left in the sand, two male forms A², shown in Fig. 11, which for distinction we may call shrunk male chills or forms. Sixth. We cut away the dove-tail bevel from one of the shrunk male forms or chills, taking great care to leave the base of the duff flange intact, producing what we call the male guide lug chill C' which is shown in Fig. 12. Seventh. We next use the shrunk male chill or form A² and the female form or chill B², embedding the same, together in the sand, as shown in Fig. 13. Then after withdrawing the female chill B², we cast from the embedded male chill A² and the impression left in the sand (as shown in Fig. 14), what we call, the final female chill, shown in Fig. 15. A large number of these final female chills B² may be cast, and kept in stock, for use in connection with patterns which have been fitted for co-operation with the same. Eighth. We next use the dressed or guide lug chill C' in co-operation with the female form or chill B², embedding the same, together in the sand, as shown in Fig. 16, and then, after withdrawing the female chill B² from the sand, we cast from the impression thus left in the sand and the embedded dressed or male guide-lug chill C' (as shown in Fig. 17), what we call the female guide lug chill D', which is shown in Fig. 18. Ninth. We next use the female guide lug chill D' in co-operation with the face plate E, shown in Figs. 19 and 20, having pin seats e, and in co-operation with rivet pins e' inserted into the said seats, to produce the guide lugs C², as shown in Figs. 20, 21 and 22. A large number of these guide lugs C² each having the rivet studs, as shown in Fig. 22, are thus cast and kept in stock. Tenth. We next rivet the guide lugs C² to the pattern F, of the stove plate or other desired article, in the proper positions, in pairs, if making stove duffs, as shown in Figs. 23, and 24. Eleventh. The final female chills B³, together with the pattern F with the guide lugs secured thereto, are embedded together in the sand, as shown in Fig. 25, the female chills B³ being used in pairs, and the guide lug C² on the pattern F serving to accurately position the chills B³. The pattern F together with the guide lugs is then withdrawn, leaving in the sand the chills B³ and the impression of the pattern, as shown in Fig. 26. Twelfth. The stove-plate H, or other article, with the duff K or leg socket is then directly cast therefrom. The said final plate or casting being shown in cross section and bottom plan in Figs. 27 and 28 of the drawings. It is evident that when the duff is produced in this way, the flanges of the same will be

an exact reproduction of the flange on the shrunk male form A²; and that both flanges of the duff and all flanges used on the pattern will be of exactly the same flare. Hence, if the stove-leg shanks be made uniform, they will fit any duff or leg socket of the stove. The same pattern with the guide lugs and the same female chills B³ may, of course, be used over and over again indefinitely. The female chills B³ might also be used on any other pattern, provided a uniform duff flange was adopted or desired on other designs of stoves. For new designs or other patterns, new guide lugs, would, of course, have to be made, as the rivet studs are only capable of use on one pattern.

The steps above described insure absolutely accurate results, inasmuch as the final female chill B³ and the guide lug C² have been produced from corresponding forms, and are of the same shrinkage. In case it is not thought worth while to attempt such great accuracy, several of the steps above specified may be dispensed with. Very good duffs, such as would probably answer most practical purposes may be produced by employing only a part of the above specified steps of the process. For example, the wooden form B' might be dispensed with and the outside shape or draft lines for the female chill B² be set in the sand by hand. The exterior form of the chill B² does not need to be particularly exact, the only important point being that its draft lines should be of such slope as is necessary for its proper withdrawal from the sand. Again, the female chill B² might be treated as the final chill, and the intermediate steps from the fifth to the tenth be omitted. In other words, the female chills B² might be made in sufficient number and be themselves used in connection with the pattern to produce the casting with the desired duff flanges, care being taken, in any suitable way to properly position the chills B² on or with the pattern in the sand, in such a way that they will preserve their location when the pattern is withdrawn. Again, the forms A² and the guide lug form or chill C' might be made by hand or machinery and treated as the originals, from which to produce the desired female chills for the duff flanges and the desired female chills from which to produce the guide lugs C². Again, instead of using the female chill B² with the male guide lug C' to produce the female guide lug D', the exterior form of the said female guide lug D' might be made in the sand by hand.

The process herein described though seeming tedious in description, is very speedily applied in practice, enabling the plates with the desired duffs or leg sockets to be produced very cheaply.

The use of the independent female chills in connection with the pattern having suitable guide lugs for positioning the chills in the sand, as shown in Fig. 25 is a great con-

venience over any plan hitherto applied so far as we are aware on account of the fact that they may be readily withdrawn from the duff flanges on the plate, regardless of their position. It is not absolutely necessary that the guide-lugs should be of the exact form shown in the said Fig. 25. Supposing said independent female chillsto have been accurately made, any kind of guide-lugs might be employed on the pattern which would result in accurately positioning the said chills in the sand. It will of course be understood that when the duffs are formed by our invention as described, that no filing or dressing of the duff flanges is required.

What we claim, and desire to secure by Letters Patent, is—

1. The method of producing cast metal duffs which consists in:—making an original male form or chill of the desired shape of duff flange and an original female form freely fitting over said male form and having its exterior shaped for reverse draft; embedding the two originals, when fitted together, in the sand and withdrawing the female member; casting from said embedded male form and the impression left by the female form, a number of female forms or chills; embedding the cast

female chills in pairs properly positioned, with the pattern of the desired article in the sand and withdrawing the pattern; and finally casting the desired article from the embedded female chills and the impression left by the pattern.

2. Molding devices, for producing cast metal duffs, comprising an original male form having the shape of the desired duff flange and secured on a base having its exterior shaped for draft in the same direction; and a female original form fitting over the said male form and having its exterior formed for draft in the reverse direction, whereby female chills may be produced having interiors of the exact form of the male original, and exteriors of the exact form as the exterior of the female original, adapted for use in connection with the pattern of the article to cast the plates with duff flanges, substantially as described.

In testimony whereof we affix our signatures in presence of two witnesses.
